EXPANDABLE FOOT COVERING

Marjorie Ellis Raney, New York, N. Y.

Application April 18, 1952, Serial No. 282,994

2 Claims. (Cl. 36—9)

This invention relates to an expandable foot covering or bootee for infants that may be worn with an equally satisfactory fit during the entire period from birth until the infant begins to walk and is in need of a conventional type of hard-soled shoe or boot that offers more support for the feet.

As a general rule, infants require warm foot covering during the first year of their lives for reasons of health. This need has traditionally been met by the well-known type of inflexible knitted or cloth bootees or leather shoes, which are arbitrarily constructed to predetermined size and shape and hence must be purchased considerably over-size or frequently replaced to accommodate the rapidly growing foot of the infant. Otherwise, the bootee or shoe becomes too tight, and the proper development of the infant's foot may be seriously impaired. It is unsatisfactory to purchase over-size bootees because of the difficulty of keeping them on the infant's foot without drawing the fastening means so tight that the proper circulation of the blood is impaired. Therefore, frequent replacement is essential, with the result that the expenditure required for foot covering during approximately the first year of a child's life is a considerable and often a burdensome amount.

A principal object of the instant invention is to eliminate the necessity, and attendant cost, of providing the infant with several pairs of conventional boots of various sizes during the first year period of rapid growth of the child, and to provide a more comfortable and healthful bootee for this purpose, adapted to permit the free development of the infant's foot without the constriction of an inflexible, hard pair of leather shoes or an inflexible pair of knitted or cloth bootees.

A further object of this invention is to provide a warm, flexible infant's bootee that will adjust easily and comfortably to the rapidly changing size of the growing infant's foot, while at the same time maintaining an attractive appearance, and having a simple means for retaining the bootee on the foot with uniform effectiveness throughout the period of use of the bootee.

Another object of the invention is to provide a bootee of the type described that will be simple to manufacture and have a low initial cost.

A broader object of the invention is to provide a flexible foot covering adapted to adjust itself to varying foot lengths.

Further objects and advantages of the invention will be apparent as the description progresses.

Briefly, the invention is exemplified by an infant's bootee constructed principally of two pieces of flexible and preferably warm material, such as knitted wool or an equivalent material that will stretch in two directions. One of the pieces serves to provide the equivalent of the sole and heel portions of the conventional boot and extends up the rear part of the leg to a region well above the ankle bones and forwardly about half-way around the leg. The other piece forms the equivalent of the upper portion of the conventional boot and complements the

2

first piece, to which it is joined, as by stitching, in the manner shown on the drawing, to form a bootee having a toe shape corresponding to that of the conventional moccasin type but differing radically therefrom in the heel construction, in that no definite heel shape is built into the bootee, thereby allowing for the adaptation of the "toe-to-heel" dimensions to the changing needs of the infant.

The problem of retaining the bootee securely on the infant's foot without the necessity of employing fastening means so snug as to prevent proper circulation of the blood is solved by the simple expedient of a drawstring adapted to be inserted through one row of a series of vertically spaced rows of eyelets arranged circumferentially of the leg-embracing portion of the bootee in the general region of the ankle bones. When the foot is small, the lowermost row of holes falls just above the ankle bones, and the drawstring may be inserted in this row of holes to retain the bootee without having to be tightened unduly, inasmuch as the drawstring does not slip over the ankle bones when tightened to only a comfortable degree. As the foot grows, and more of the leg portion becomes in effect foot portion, the higher rows of holes come successively into use.

The invention and the manner of making it will be more clearly understood by reference to the detailed description that follows of the preferred embodiment illustrated on the drawing, in which:

Fig. 1 is a side elevation showing the bootee in full lines, with the drawstring in the lowermost row of holes, as it would be worn on an infant of an age of perhaps two weeks, and in dotted lines, with the drawstring in the second or intermediate row of holes, as it would be worn on an infant of an age of perhaps six months, whose foot has outgrown the smaller foot length;

Fig. 2 is a perspective view showing the bootee of this invention as worn by an infant about two weeks old; and,

Fig. 3 is a perspective view showing the bootee as worn by an infant about one year old.

In the embodiment illustrated by the drawing, the invention comprises upper and lower pieces indicated in their entirety by the reference characters 1 and 2, respectively, and fashioned of a flexible and preferably warm material that will yield and stretch in two directions. For example, pieces 1 and 2 may be formed of knitted wool, but any equivalent flexible material may be employed.

Pieces 1 and 2 are formed separately, prior to assembly, to approximately plane developments of the general shape indicated, without, however, the formation of a special, enlarged heel- or quarter-forming portion in piece 2. The piece 1 has a curvate lower forward portion 3 simulating in general the curvature of the forward, tip or toe portion of the human foot and, in the preferred embodiment shown, the curvature of the toe portion of a conventional moccasin-type boot, to which it corresponds. Piece 1 also has an elongated toe and instep portion 4 extending rearwardly and upwardly and terminating in an upper edge 5, the portion 4 forming the front or forward leg-embracing and upper instep-covering portions of the assembled bootee.

Piece 2 has a curvate, lower portion, as indicated generally at 6, this portion being made wide enough to provide at the toe of the assembled device, in effect, both a sole portion 7 and the "walls," or wall equivalents, 8 of the toe, these corresponding to similar portions of the conventional moccasin-toe bootee. As indicated by the reference numeral 9, piece 2 has an elongated portion extending rearwardly and upwardly from portions 7 and 8 and which forms the rest of the sole, the lower arch-embracing portion, the heel-embracing or quarter portion, and the rear leg-embracing portion of the assembled bootee, and terminates in an upper edge 10. The quarter

portion is made long enough to provide ample fullness in the heel region to allow for expansion into a greater sole or foot length, with the upper edge 10 of the elongated portion 9 aligning with or complementing upper edge 5 of the upper portion of piece 1 to define the upper margin of the leg portion of the assembled bootee. Portions 4 and 9 cooperate to form the foot-and-leg-embracing portions of the assembled article, which as will be clear from the preceding description, comprise that portion of the bootee extending rearwardly and upwardly from the toe portion of the assembled article, as formed from the toe portions 3 and 6 of the pieces 1 and 2.

It will be seen that no definite or fixed heel shape and no fixed toe-to-heel dimension is built into the bootee of this invention, neither of the pieces 1 and 2, nor the assembled device, having an arbitrary dividing line established between the foot and leg portions. The portion of the bootee serving as a "foot" portion at any particular stage in the life of the infant thus is determined by the size to which the infant's foot has developed at the particular time, the bootee adapting itself readily to the changing foot-size requirements.

The only adjustment required during the life of the bootee is the adjustment of the means for retaining it on the infant's foot. This is an exceedingly simple adjustment when the retaining means take the preferred form illustrated on the drawing. As shown, a plurality of vertically spaced rows 11, 12, and 13 of eyelets or apertures 14, arranged and spaced circumferentially of the leg portion formed jointly by the portions 4 and 9, accommodate a drawstring 15, which may be inserted in the eyelets of a selected row and tightened to reduce the effective circumference of the upper in that particular region, to hold it against slipping below the ankle bones. The bottom row of holes 11 is located so as to fall just above the ankle bones of an infant about two weeks old. The additional rows 12 and 13 are spaced successively vertically higher than the row 11, and so as to in turn fall just above the ankle bones and receive the drawstring when the infant is of an age of approximately six months and one year, respectively.

The number of rows of eyelets can be increased or decreased, depending upon the number of adjustments desired, and other retaining means may be employed in lieu of, or in addition to, the drawstring and eyelets. It is important, however, to employ a type of retaining means that can be located just above the ankle bones at all stages of wear, so that the leg portion can be tightened sufficiently in that local area to resist slipping over the ankle bones but without having to be tightened to the point where circulation of the blood is impaired.

In making the foot covering according to the method of the instant invention, the pieces 1 and 2 are preformed, as by knitting, and placed together in complementary fashion, and the curvate portions forming the toe, and the adjacent edges of the leg-embracing portions, from the top down to the bottom row of eyelets, are secured together first, as by sewing. The order of performing these initial securing steps is not critical. Thereafter, working from the secured portions toward the quarter portion, the sewing or stitching together of the two pieces of material adjacent their lateral edges is progressively continued to form the completed line of stitching illustrated by the dotted line 16. While the stitching is thus being completed, the material of portion 9 is stretched or pulled, to form a fullness at the quarter, which is not all taken up again by such natural resilience as the material may have, but which is retained at least in part after the stitching is completed, and thus facilitates the accommodation of the heel of the wearer. A hem may be provided at the top of the upper portions as shown at 17 by the dotted line. All of the other edges may be overcast to prevent ravelling. In making the bootee of this invention, it is of primary importance to avoid the establishment of a definite and invariable foot length, this being

accomplished by providing as the only suggestion of a heel a fullness in the general region of the portion of piece 2 in which the heel will fall during the varying stages of growth of the foot.

From the foregoing description, it will be seen that I have disclosed a preferred embodiment of the invention that will provide the advantages sought, but it is to be understood that this description is to be construed as merely illustrative and not in a limiting sense, the scope of the invention being defined by the subjoined claims.

What I claim is:

1. A foot covering for the human foot comprising a first piece of flexible material capable of stretching in two directions having a curvate lower, forward portion simulating in general the curvature of the forward, toe portion of the human foot and an elongated upper portion extending rearwardly and upwardly and terminating in an upper edge, said upper portion forming the front leg-embracing and instep-covering portion of the foot covering, a second piece of flexible material capable of stretching in two directions having a curvate lower, forward portion shaped and dimensioned complementally to the lower, forward portion of the first piece and providing forward sole and wall equivalents in the foot covering, said second piece having an elongated rearwardly extending portion extending rearwardly and upwardly from its lower, forward portion and terminating in an upper edge which complements the upper edge of said upper portion and combines therewith to form the upper edge of the leg portion of the foot covering, said elongated rearwardly extending portion of the second piece forming the rest of the sole, the shank portion, the quarter portion, and the rear leg-embracing portion of the foot covering, and having a portion of extra fullness extending over the general region in which the heel of the foot normally will fall, so that no predetermined foot length is built into the foot covering and the foot covering adjusts itself to varying foot sizes, said first and second pieces being joined together at their forward and lateral edges throughout substantially their entire lengths to form the unitary foot covering, said elongated rearwardly extending portion and said upper portion having a plurality of circumferentially extending sets of vertically spaced alternatively utilizable fastening retaining means located in the region above the portion of extra fullness and at least one of which will normally fall just above the ankle bones of the wearer for selection to decrease the effective combined circumference of the elongated rearwardly extending portion and the upper portion in that region to hold them against slipping below the ankle bones.

2. A foot covering as defined in claim 1, in which said fastening retaining means comprise a plurality of spaced apertures arranged in circumferentially extending and vertically spaced rows so located as to fall respectively just above the ankle bones as the foot length of the wearer varies and thereby exhausts or increases the length of the leg-embracing portion of the foot covering, and a drawstring insertable in a selected row of apertures next above the ankle bones for decreasing the effective circumference in the region local to the selected row.
